UNITED STATES PATENT OFFICE

154,815

DESIGN FOR A JUVENILE VEHICLE

William I. Smith, Perrysburg, Ohio, assignor to
The Hettrick Manufacturing Company, Toledo,
Ohio, a corporation of Ohio

Application August 12, 1948, Serial No. 148,073

Term of patent 14 years

(Cl. D34—15)

To all whom it may concern:

Be it known that I, William I. Smith, a citizen of the United States and a resident of Perrysburg, Wood County, Ohio, have invented a new, original, and ornamental Design for a Juvenile Vehicle, of which the following is a specification, reference being had to the accompanying drawing, forming a part thereof.

In the drawing:

Figure 1 is a front perspective view of the juvenile vehicle, showing my new design; and

Figure 2 is a rear end perspective view of the juvenile vehicle.

I claim:

The ornamental design for a juvenile vehicle, as shown.

WILLIAM I. SMITH.
